UNITED STATES PATENT OFFICE.

WILLIAM A. HYLE, OF BUFFALO, NEW YORK, ASSIGNOR TO SAFETY FIRST LOCK COMPANY, OF BUFFALO, NEW YORK, A CORPORATION OF NEW YORK.

LOCK.

1,174,253.

Specification of Letters Patent.

Patented Mar. 7, 1916.

Application filed May 10, 1915. Serial No. 26,983.

To all whom it may concern:

Be it known that I, WILLIAM A. HYLE, a citizen of the United States, residing at Buffalo, in the county of Erie and State of New York, have invented new and useful 5 Improvements in Locks, of which the following is a specification.

This invention relates to a lock which is more particularly designed for holding 10 window sashes in position but which may also be used for a variety of other purposes where a small and compact lock is required which can be quickly shifted into an open or closed position without the use of a key.

15 It is the object of this invention to provide a lock of this character which is simple and durable in construction, efficient in operation and composed of few parts which can be produced and assembled at comparatively low cost.

20 In the accompanying drawings: Figure 1 is a rear elevation of my improved lock showing the rear wall thereof removed and the operating shaft in section and the parts 25 shifted in such a position that the locking bolt is shot or in its operative position. Fig. 2 is a similar view showing the parts shifted in a position in which the locking bolt is in its retracted or open position. 30 Fig. 3 is a vertical transverse section taken in line 3—3, Fig. 1, but showing the rear wall of the casing in place and the lock as a whole mounted on a support. Fig. 4 is a horizontal section taken in line 4—4, Fig. 35 2 and showing the rear wall in place.

Similar characters of reference indicate corresponding parts throughout the several views.

Although the casing of this lock may be 40 variously constructed the form shown in the drawings is preferred and as there shown in the same comprises a body portion having an upright front wall 1, upper and lower longitudinal guideways 2, 2 projecting inwardly from the upper and lower edges of the front wall, two fastening webs 3, 3 projecting outwardly from the rear edges of the guideways and arranged parallel with the front wall, two marginal 45 flanges 4, 4 arranged lengthwise at the outer edges of the fastening webs and projecting inwardly or rearwardly therefrom and two transverse guide flanges 5, 5 arranged vertically at the front and rear ends of the 50 front wall, guideways, fastening webs and

marginal flanges and having their rear edges flush with the rear edges of the marginal flanges. The hollow space or chamber within this body is closed on its rear side by means of a rear wall 6 which is arranged within the guide flanges and the marginal flanges and bears with the upper and lower parts of its inner side against the fastening webs. When this lock is assembled the same may be secured with the 60 rear side of the casing bearing against the surface adapted to receive the lock by means of a plurality of screws 7 or the like passing through corresponding openings 8, 9 formed in the fastening webs and the upper and lower parts of the rear wall and 65 engaging with the support 10 which is adapted to receive the lock, as shown in Fig. 3. The body of this casing is preferably stamped from a single sheet of metal 70 although the same may be cast or otherwise formed if desired, and the rear wall thereof is also preferably formed of a sheet of metal 75

Within the compartment or chamber of 80 the casing is arranged a yoke 11 which is slidable in the casing and guided during this movement by engagement of its upper and lower longitudinal guide edges with the inner sides of the guideways 2, 2 on the 85 upper and lower parts of the casing body, as shown in Figs. 1, 2 and 3. At its vertical front end the sliding yoke is provided with a forwardly projecting locking bolt 12 which is arranged in a guide opening 13 90 formed in the adjacent front guide flange or wall of the casing, and at its rear end the yoke is provided with a rearwardly projecting guide shank 14 which is arranged in a guide opening 15 formed in the rear 95 guide flange or wall of the casing. This yoke and the locking bolt and guide shank are preferably constructed in a single piece by stamping the same from a sheet of metal but if desired the same may be otherwise 100 constructed. In the preferred form of this yoke its locking bolt and guide shank are arranged centrally or midway of the height of the yoke and the bolt and shank are preferably made of different widths, for instance the locking bolt may be somewhat narrower than the guide shank, as shown in Figs. 1 and 2, and the guide openings which receive these members are made of 105 corresponding dimensions. By this means 110

it is impossible to assemble the yoke with its bolt and shank in the body of the casing in an improper manner because the shank will not enter the guideway of the locking bolt, thereby enabling these parts to be assembled quickly and properly and reducing the cost of the same accordingly.

In its central part the yoke is provided with an opening 16 which is constructed to 10 form front and rear thrust shoulders 17, 18 which are arranged vertically or perpendicularly to the line of travel of the yoke. At the corresponding ends of the thrust shoulders, preferably adjacent to the lower ends 15 thereof, the opening 16 is constructed to form a stop shoulder 19 which is of curved concave form. Within this opening of the yoke is arranged a rotatable eccentric 20 which is pivotally mounted on the casing 20 and whereby the yoke is shifted lengthwise in the casing. This eccentric is preferably of circular form on its periphery and of a diameter equal to the distance between the front and rear thrust shoulders so that upon 25 turning the eccentric in one direction or the other the highest part of its face will engage alternately with these thrust shoulders and move the yoke so that in one extreme position of the same the locking bolt will be shot 30 or projected into its operative position, as shown in Fig. 1, while in the other extreme position of the same the locking bolt will be retracted into its inoperative position, as shown in Fig. 2. The stop shoulder is preferably so located relatively to the eccentric that the same arrests the rotary movement of the eccentric in either direction after the highest part of the eccentric has passed slightly beyond or below a dead center line 35 drawn lengthwise through the axis of the eccentric and the front and rear thrust shoulders, thereby serving to positively hold the yoke against longitudinal movement while the eccentric is in either of these extreme positions. This will be apparent upon 40 an examination of Figs. 1 and 2 in which Fig. 1 shows the eccentric engaging its highest part with the front thrust shoulder slightly below said dead center line and its underside engaging with the stop shoulder, in which position of the parts it is impossible to move the yoke by external pressure applied lengthwise to the locking bolt so 45 that the latter at this time is securely held in its locked or shot position. The same is true when the eccentric is turned to its fullest extent in the opposite direction in which the highest part of its face is slightly below said dead center line and its underside 50 engages with the stop shoulder, in which position of the parts the yoke is also held against movement by external pressure applied lengthwise to the bolt so that the latter is positively held in its retracted position.

60 Although the movement of the yoke may be

effected solely by operation of the eccentric it is preferable to associate with this yoke a spring pressing device which operates constantly to move the yoke in a direction for shifting its locking bolt into an operative 70 position so long as the eccentric has not been shifted fully into its rearmost position. The preferred means for this purpose comprise two springs 21, 21 arranged within the casing above and below the guide shank and each engaging its inner end with the rear edge of the yoke and its outer end with the inner side of the adjacent rear guide flange. By means of these springs this lock may be utilized as a spring catch so that by withdrawing or retracting the locking bolt upon 75 turning the eccentric back slightly and then again releasing the same the yoke and locking bolt will be again projected into their operative position by the springs 21. By 80 this means this lock may be utilized not only as a positive lock in which the bolt may be held either in its projected or retracted position but may also be utilized as a spring catch.

90 Any suitable means may be provided for pivotally mounting the eccentric on the casing but the means which are shown in the drawings are preferably designed to also form the connection between the body and rear wall of the casing so that these parts will not become dismembered when the lock is not mounted. The preferred means for this purpose which are shown in the drawings comprise a shaft having a flat sided 95 central part 22 which engages with the correspondingly shaped opening 23 in the eccentric, a round rear part 24 which turns in a bearing opening 25 in the rear wall of the casing, a round front part 26 which turns in 100 a bearing opening 27 in the front wall of the casing, and a handle, fingerpiece or button 28 arranged on the front end of the shaft outside of the front wall of the casing. This handle and shaft are preferably constructed from a single piece of metal by casting or otherwise. As the round parts 24, 26 of the shaft are on opposite sides of the square central part which carries the eccentric the latter is reliably mounted on the 105 casing so that the same will not tip to one side and bind but is always free to turn in one direction or the other upon manipulating the handle on the exterior of the casing for this purpose. The flat sided central part 110 of this shaft is somewhat smaller than the front round part thereof and somewhat larger than the rear round part thereof which permits this shaft to be passed successively through the front wall of the casing, then through the eccentric and then through the rear wall of the casing for the purpose of assembling the parts and still enable this shaft and the handle to be made of one piece. After the parts have been thus 115 120 125 130

assembled the rear end of the shaft is upset so as to form a head 29 thereon which engages with the rear or outer side of the rear wall. By this means the body and rear 5 wall of the casing are held together by reason of the handle of the shaft engaging with the outer side of the front wall and the rear head thereof engaging with the outer side of the rear wall, thereby avoiding the necessity of providing other means for connecting these parts of the casing and confining the working parts within the same.

It will be apparent from the foregoing that this lock consists of very few parts 15 compared with locks which accomplish the same purpose and that these parts are all simple and durable in construction, the same are not liable to get out of order and are also capable of being produced economically so 20 that this lock can be marketed at a comparatively low price.

I claim as my invention:

1. A lock comprising a casing, a yoke slidably mounted on said casing and provided 25 with a locking bolt and with an opening forming two end thrust shoulders which face each other, a stop shoulder arranged adjacent to corresponding lower ends of both thrust shoulders, and a clearance space between 30 the upper ends of said thrust shoulders, and a rotatable eccentric mounted on the casing and adapted to move through said clearance space and to engage its highest part with either of said thrust shoulders for 35 shifting the locking bolt into an open or closed position and also adapted at either end of its rotary movement to stand with its highest part slightly beyond a dead center line drawn through said thrust shoulders 40 and the axis of said eccentric and to engage with said stop shoulder at either end of its rotary movement for locking said bolt either in its open or in its closed position.

2. A lock comprising a casing, a yoke slidably mounted on said casing and provided 45 with a locking bolt and with an opening forming two end thrust shoulders which face each other, a stop shoulder arranged adjacent to corresponding lower ends of both thrust shoulders, and a clearance space between 50 the upper ends of said thrust shoulders, a rotatable eccentric mounted on the casing and adapted to move through said clearance space and to engage its highest part with

either of said thrust shoulders for shifting 55 the locking bolt into an open or closed position and also adapted at either end of its rotary movement to stand with its highest part slightly beyond a dead center line drawn through said thrust shoulders and the axis 60 of said eccentric and to engage with said stop shoulder at either end of its rotary movement for locking said bolt either in its open or in its closed position and a spring arranged in said casing and pressing 65 constantly against said bolt for moving the same in the direction in which the bolt is projected.

3. A lock comprising a casing having a body consisting of a front wall, longitudinal 70 guideways projecting inwardly from opposite longitudinal edges of said front wall, fastening webs projecting outwardly from the inner edges of the guideways and each provided at its outer edge with an inwardly 75 projecting marginal flange, and transverse guide flanges arranged at opposite ends of the front wall, guideways, fastening webs and marginal flanges, and a rear wall arranged within the guide flanges and marginal flanges and engaging said fastening webs, a yoke arranged within the casing and engaging its longitudinal edges with said guideways and provided at its opposite transverse ends with a locking bolt and a 80 guide shank which are guided on said 85 guide flanges, and an eccentric rotatably mounted on said casing and operatively engaging said yoke.

4. A lock comprising a casing having a 90 body provided with a front wall having a bearing opening and a rear wall having a bearing opening, a yoke slidable lengthwise in the casing and having a locking bolt, an eccentric for operatively engaging said yoke 95 for shifting the same and provided with a flat sided opening, and means for turning said eccentric comprising a shaft having a flat sided central part engaging with the opening of the eccentric, a round inner end 100 turning in the bearing opening of the rear wall and a round front end turning in the bearing opening of the front wall, and a handle arranged on the front end of the shaft, the rear end of said shaft being upset 105 to form a head which engages with the outer side of said rear wall.

WILLIAM A. HYLE.
